(57) **CLAIM**

The ornamental design for a mobile with hanging angels, as shown and described.

DESCRIPTION

FIG. 1 is a perspective view of our design;

FIG. 2 is a side elevational view of our design, the opposite view being a mirror image thereof;

FIG. 3 is a top view of our design;

FIG. 4 is a back elevational view of our design; and,

FIG. 5 is a front view of our design.

The broken lines are included for the purpose of illustrating portions of the mobile with hanging angels that form no part of the claimed design.
